UNITED STATES PATENT OFFICE.

FREDERICK C. BARGAR, OF COLUMBUS, OHIO, ASSIGNOR TO NU-EX FIRE APPLIANCE COMPANY, OF COLUMBUS, OHIO, A CORPORATION OF OHIO.

FIRE-EXTINGUISHER.

1,338,166.

Specification of Letters Patent. Patented Apr. 27, 1920.

Application filed November 6, 1916. Serial No. 129,682.

To all whom it may concern:

Be it known that I, FREDERICK C. BARGAR, a citizen of the United States, residing at Columbus, in the county of Franklin and State 5 of Ohio, have invented certain new and useful Improvements in Fire-Extinguishers, of which the following is a specification.

This invention relates to fire extinguishers and is particularly directed to the 10 supporting and casing structure used in connection with containers adapted to hold the extinguishing chemical and expelling fluid, the container and surrounding casing being so constructed that the user at all 15 times may have a visual indication of the fluid level within the container. Specifically, the fire extinguisher structure includes a glass container and a metallic surrounding shell, which latter is provided with a 20 sight opening, so that the liquid level may be readily ascertained. In combination with these, my invention consists in providing 25 a packing to securely hold the container within the shell, which packing is constructed of strands diagonally arranged with respect to the center line of the extinguisher as a whole, so that none of the 30 strands will completely obscure the liquid level from view.

35 A further object of this invention consists in combining with the shell and container, a metallic packing made of wire strands interwoven with each other, corrugated and diagonally arranged so that the above objects are further carried out.

The preferred embodiment of my invention is shown in the accompanying sheet of drawings, in which similar characters of reference designate corresponding parts, 40 and in which:

Figure 1 shows a fire extinguisher partially in section to disclose my improved type of packing in combination therewith, and,

45 Fig. 2 is a horizontal section of the structure shown in Fig. 1.

In these views, the extinguisher is shown as comprising an outer shell or casing 1, provided with diametrically opposed sight 50 openings 2. This shell surrounds a glass container 3, which container is adapted to hold the extinguishing chemical and an expelling fluid such as compressed air. This glass container is suitably packed within

the shell to guard against longitudinal displacement by means of any preferred type of packing shown at 4 and 5, as being located adjacent the lower and upper ends respectively. Between these points, I have provided a metallic packing in the nature of 55 a wire netting 6, whose strands are diagonally arranged with respect to each other and which netting as a whole is corrugated to yieldingly center the container within the shell. In assembling, the container may 60 be wedged in position and held in such position by means of the corrugations of the netting. By means of the diagonal arrangement of the wire strands, none of these strands will entirely obscure the liquid level 65 through the sight openings 2 from view, as might be the case if the strands forming this netting were horizontally and vertically arranged. In this latter case, the horizontal strands might appear at the liquid 70 level and where this liquid and the expelling fluid or compressed air are not discernible by color variation, this latter feature would be very objectionable. Further, this wire netting permits the packing to be 75 placed over the sight opening and in this manner gives an additional safe guard against breaking by a blow from the exterior. It may also be pointed out that by arranging the wire strands diagonally and 80 then corrugating the netting as a whole, all of the wires constituting the netting or packing are bent to conform to the corrugation, which would not be the case if these wires ran vertically and horizontally and 85 then the horizontal wires corrugated only.

What I claim, is:

1. In a fire extinguisher, a substantially transparent container adapted to hold an extinguishing chemical and an expelling pressure fluid, a shell surrounding said container, said shell being provided with a sight opening to disclose the liquid level, and a foraminated packing located between said shell and container and extending over 95 said sight opening.

2. In a fire extinguisher, a substantially transparent container adapted to hold an extinguishing chemical and an expelling pressure fluid, a shell surrounding said container, said shell being provided with a sight opening to disclose the liquid level and a packing located between said shell 100 and a

and container formed of non-horizontal strands at the point where it underlies said sight opening.

3. In a fire extinguisher, a substantially transparent container adapted to hold an extinguishing chemical and an expelling pressure fluid, a shell surrounding said container, said shell being provided with a sight opening to disclose the liquid level, and a packing located between said shell and container formed of corrugated wire netting having the strands thereof diagonally arranged with respect to the normal liquid level.
5. In a fire extinguisher, a substantially transparent container adapted to hold an extinguishing chemical and an expelling pressure fluid, a shell surrounding said container, said shell being provided with a sight opening to disclose the liquid level, and a packing located between said shell and container and extending over said sight opening, said packing being permeable as to sight through said sight opening to disclose the liquid level to an observer.
10. 4. In a fire extinguisher, a substantially transparent container adapted to hold an extinguishing chemical and an expelling pressure fluid, a shell surrounding said container, said shell being provided with a sight opening to disclose the liquid level, and a packing located between said shell and container formed of corrugated wire

netting having the strands thereof diagonally arranged, said corrugation being arranged to cross said strands in non-parallel relation.

15. 5. In a fire extinguisher, a substantially transparent container adapted to hold an extinguishing chemical and an expelling pressure fluid, a shell surrounding said container, said shell being provided with a sight opening to disclose the liquid level, and a packing located between said shell and container and extending over said sight opening, said packing being permeable as to sight through said sight opening to disclose the liquid level to an observer.

In testimony whereof I affix my signature in presence of two witnesses.

FREDERICK C. BARGAR.
